United States Patent Office.

JOHN BURNHAM, OF BATAVIA, ILLINOIS.

Letters Patent No. 82,689, dated October 6, 1868.

IMPROVED TRUSS.

The Schedule referred to in these Letters Patent and making part of the same.

TO ALL WHOM IT MAY CONCERN:

Be it known that I, JOHN BURNHAM, of Batavia, in the county of Kane, and State of Illinois, have invented a new and improved Truss; and I do hereby declare that the following is a full, clear, and exact description thereof, which will enable those skilled in the art to make and use the same, reference being had to the accompanying drawings, forming part of this specification.

This invention relates to a new and useful improvement in trusses, and it consists in attaching the pad-lever to the band by means of a ball-and-socket joint, substantially as hereinafter fully shown and described, whereby the pad may be adjusted in any desired position to press properly on the rupture, and to suit either a flat or prominent abdomen; and also to convert the truss into a right or left one; that is to say, so that it may be adjusted to the right or left side of the body, as may be required.

The accompanying drawing represents a perspective view of my invention.

A is the strap of the truss, in which the steel or metal band is fitted, as usual, and B is a socket at the end of the band, composed of two parts, *a b*, connected together by screws, *c*, and having a concave, which is a portion of a hollow sphere, to receive a ball, *d*, the parts *a b* being made to press against the ball, in a greater or less degree, by means of the screws *c*.

The ball *d* has an arm, *e*, projecting from it, and from this arm *e* the pad-lever *C* projects, at right angles, the pad *D* being attached to the outer end of the lever *C*, as usual, or in any proper way.

By thus connecting the pad-lever *C* to the spring, by means of a ball-and-socket joint, the pad may be adjusted in any desired position, so as to press properly upon the rupture, and when properly adjusted, may be secured firmly in position by screwing the two parts, *a b*, of the socket together, so that the ball *d* will be tightly grasped; and the truss may be applied to either side of the body, as the pad-lever *C* may be swung entirely around, and the pad adjusted to either side of the lever.

I do not confine myself to the precise construction of a ball-and-socket joint, as herein shown and described, for that may be varied or modified in different ways, and the same end attained.

I claim as new, and desire to secure by Letters Patent—

The attaching of the pad-lever *C* of the truss to the spring, in the band or strap thereof, by means of a ball-and-socket joint, substantially as shown and described.

JOHN BURNHAM.
